Des. 231,267
Patented Apr. 9, 1974

231,267

DIAZO COPYING MACHINE OR SIMILAR ARTICLE

Paul Matwey, Binghamton, N.Y., assignor to
GAF Corporation, New York, N.Y.

Filed Oct. 18, 1971, Ser. No. 190,441

Term of patent 14 years

Int. Cl. D16—03

U.S. Cl. D61—1 Q

FIG. 4FIG. 3FIG. 1 is a top, front and right side perspective view of a diazo copying machine or similar article showing my new design;

FIG. 2 is a left side elevational view thereof;

FIG. 3 is a front elevational view thereof;

FIG. 4 is a rear elevational view thereof.

I claim:

The ornamental design for a diazo copying machine or similar article, substantially as shown.
